UNITED STATES PATENT OFFICE.

FRANK S. ALIANO, OF NEW YORK, N. Y.

LOCK.

No. 885,214.

Specification of Letters Patent. Patented April 21, 1908.

Application filed November 18, 1905. Serial No. 287,918.

To all whom it may concern:

Be it known that I, FRANK S. ALIANO, a citizen of the United States, residing at the borough of Brooklyn, in the city of New York, county of Kings, and State of New York, have invented certain new and useful Improvements in Locks, of which the following is a specification, reference being had therein to the accompanying drawings, which 10 form a part thereof.

My invention relates to locks, and more particularly to a class of trunk locks employing a swinging hasp and a bolt or bolts adapted to be automatically actuated in closing 15 the lock.

The main object of the invention is to provide a lock wherein the bolt or bolts will be seated within the lock cup and projected through an opening or openings in the side 20 or sides thereof, and be capable of pivotal or a swinging movement to draw them within or project them from said cup.

A further object is to provide a lock wherein oppositely acting spring pressed bolts may 25 be made in a single piece to insure uniformity in their action when locking or unlocking the lock, and by reducing the number of working parts, to cheapen the cost of production.

A further object is to provide such a lock 30 wherein the bolts will be so disposed as to insure their operation without the necessity for such accurate finishing as will render the lock liable to become inoperative through continued use and the resultant wear on contacting surfaces.

A further object is to provide a lock wherein the bolt and the key controlled mechanism actuating same, will be compactly arranged within the lock cup, and held in place through 40 the relation of the several parts to each other and to the hasp carrying said cup. And a still further object is to provide a lock of this character which will be inexpensive to manufacture.

45 The invention consists primarily in the combination in a lock of a lock cup comprising an upper or tumbler chamber, and a lower or bolt chamber of smaller dimensions than said tumbler chamber having an opening through the side thereof, a pivotal or swinging bolt mounted in said bolt chamber having its head normally projected through said opening, a spring acting on said bolt to normally project it from said bolt chamber, 50 key controlled means whereby said bolt may be swung to withdraw its head within said

bolt chamber and said bolt may rotate independently of said means, means supporting said cup, and a coöperating locking plate having an opening adapted to receive the 60 portion of said cup carrying said bolt whereby said bolt may pass through said plate and engage the under side thereof, and in such other novel features of construction and combination of parts as are hereinafter set forth 65 and described and more particularly pointed out in the claims hereto appended.

Referring to the drawings: Figure 1 is a longitudinal section of the hasp plate, the hasp and the lock or socket plate, with the 70 cup shown in elevation; Fig. 2 is a plan view of the lock cup and the lock mechanism therein, removed from the hasp; Fig. 3 is a section on the line 3—3 of Fig. 2; Fig. 4 is a plan view of the lock cup with the key controlled 75 mechanism actuating the bolt or bolts removed; Fig. 5 is a bottom view of the rotary plate, and Fig. 6 is a plan view of the lock or socket plate.

Like letters refer to like parts throughout 80 the several views.

In the embodiment of my invention shown in the accompanying drawings, A indicates the body of a trunk or chest and B the cover therefor. Attached to the trunk or chest 85 body A is a hasp plate C to which is hinged in the usual and well known manner, a hasp D carrying a lock cup containing the bolt mechanism and the key controlled mechanism for actuating same. Secured to the cover of the 90 trunk or chest B is a lock or socket plate E having a depressed portion substantially centrally thereof to form a seat for the lock cup, and having a substantially rectangular opening E' extending diagonally across said portion to permit the passage of the part of the cup carrying the bolts therethrough, and afford a suitable engaging surface for the bolts themselves. In the cheaper grade of locks 95 these parts are all made of steel pressed or 100 stamped to shape. The hasp plate C is secured in place by a single headed bolt F passed through a substantially central opening C' in said plate. This manner of attachment is desirable and is commonly employed 105 because of the facility in adjusting the hasp plate, the economy and the finish afforded by the bolt head. It has heretofore, however, been found that when a stamped hasp plate is used, the portion adjoining the bolt opening 110 is not so braced or reinforced as to give stability to the plate, and that an additional

- operation is required to provide a suitable countersink for the head of the bolt when the nature of the plate permits such. To obviate these difficulties, I stamp or draw the 5 metal centrally of said plate into a cylindrical column C^2 extending downwardly to a degree which will bring the bottom thereof into engagement with the trunk or chest cover B, and form the top of said column into a bevel 10 to form a countersink for the bolt head, at C^3 , said column thus being formed integrally with the hasp plate, and serving as a brace or reinforcement therefor to resist the strains thereon in attaching the plate to the cover.
- 15 The lock cup comprises a casing a comprising an upper cylindrical portion a' forming a tumbler and a controlling plate chamber; a lower substantially rectangular portion b extending diametrically across said portion a' 20 and opening thereinto, forming a bolt chamber, and a connecting flange or web c forming within said cup a suitable bearing for the controlling plate, and support for the tumbler and tumbler spring studs, and presenting 25 downwardly a bearing face adapted to engage and rest upon the socket plate E. A top flange a^2 is provided to facilitate the attachment of the lock cup to the hasp D. The portion b has therein at diagonally opposite points bolt openings as b' , said openings being slightly below the flange or web c . The bottom of said portion b is closed and has an opening centrally thereof for the key barrel or pin. 30
- 35 Seated in the bottom of the portion b of the cup a , as shown in Fig. 4, is the bolt mechanism. This mechanism consists of a single bolt casting composed of a central portion d pivotally mounted on the key barrel or pin e 40 by means of an opening extending through said portion, and bolt heads f adapted to project through bolt openings b' . The side of the portion d adjoining each said bolt head f as at d' , is substantially straight and parallel 45 with the walls b of the bolt chamber, thus serving as a stop for said bolt heads by engagement with said wall, the side opposite said portion d' , as at d^2 being curved on a radius to permit the free swinging or turning of 50 the bolts. A spring seat g is formed by means of a recess adjoining the bolt head, the coiled springs g' acting against said seat and the wall b of the bolt chamber. These springs g' act to normally project the bolt 55 heads f through the bolt openings b' . The lower face of the bolt heads f is beveled in the usual manner to cause the engagement of said bolts with the socket plate to force said bolts against the tension of the springs g' 60 within the bolt chamber, and the upper face of each said bolt head is parallel with and distanced from the flange or web c sufficiently to permit said bolts to be forced beneath the lock or socket plate E.
- 65 Inasmuch as the bolt heads f describe an

arc when actuated, it is necessary to curve the ends thereof at f' on a radius from the center pivot e to permit such movement. An abutment f^2 is formed on each said bolt head f within the bolt chamber and projected into the tumbler and controlling plate chamber, by means of which abutments said bolts are actuated by the key controlled actuating mechanism.

Seated on the flange or web c is a rotary 75 plate h to which is riveted on the under side thereof so as to project into the bolt chamber, a narrow plate i of substantially the width of the bolt chamber at its widest point, from which point the sides thereof converge sufficiently to permit the limited rotation of said plate h . The plate i extends into close juxtaposition to the bolt portion d and the springs g' , serving to maintain said parts in position in the bolt chamber, and one side of each end of said plate is projected as shown at i' to engage the abutment f^2 . The plate h has an opening therethrough adjoining an opening through both said plates for the key barrel, forming a key seat h' . The opening 80 for the key barrel in the plates h is larger than in the plate i , forming a seat h^2 for a shoulder on said key barrel.

The periphery of the plate h is cut away at different points to provide suitable guide surfaces contacting with the walls of the cup a , shoulders h^6 h^6 adapted to engage the abutments f^2 and ways at h^3 — h^4 for the tumbler stud j and the tumbler spring stud k , and at the same time provide a suitable support for 100 the tumbler lock piece h^5 carried by said plate h , the tumblers m and their springs n , and holding said last mentioned parts in place from beneath. The tumblers m and their springs n mounted respectively on the 105 studs j and k in the usual and well known manner are of well known construction and arrangement and will not be described more fully herein.

A washer o fitted on the studs j and k and 110 engaging the hasp D occupies any space above said tumblers and said springs, and between them and the hasp, thus preventing the displacement of these parts and the parts thereunder. The key barrel e which I preferably employ, has oppositely disposed shoulders e' e^2 adapted respectively to rest upon the seat h^2 , and engage the hasp D, and a downwardly projected end e^3 adapted to pass through the central portion d of the 120 bolt casting and serve as a pivot therefor. Said barrel is provided with the usual longitudinal slot.

The operation of the herein described lock is substantially as follows, it being assumed 125 that the various parts are in the locked position, as shown in Fig. 1. To release the hasp, or withdraw the bolts so as to release the hasp, the key is inserted in the barrel e and turned therewith actuating the tumblers m 130

against the tension of their springs n in the usual manner to free the lock piece h^s and permit the key to engage the key seat h' and rotate the plate $h-i$, the contour of the latter permitting such movement. This rotation of the said plates through the abutments h^s h^s i' i' and the coöperating abutments f^2 on the bolt heads, swings or rotates the bolt proper until said heads f are entirely withdrawn within the bolt chamber through the openings b' in the wall b thereof. The curved ends, at f' and the curved sides at d^2 permit such movement against the tension of the springs g' . The key may be removed by a reversal of this action permitting the springs g' to force the bolt heads f outwardly until they have assumed their former or locked position, the portion d' engaging the wall at b' and limiting the extent of projection thereof, the hasp D having first been raised. This restores the plate $h-i$ to its former and locked position also, permitting movement of the bolt independently thereof, however.

To lock the hasp D it is merely necessary to bring the hasp D down until the lower portion of the cup b registers with the opening E' of the lock or socket plate E , and the bolt heads f engage diagonally opposite points of said opening, whereupon slight pressure will cause said bolt heads, through the bevel thereon to recede until they are forced within the bolt chamber sufficiently to permit their passage through the said opening E' , whereupon the springs g' will immediately restore them to their former position, but beneath the said lock or socket plate E thus effectually locking said hasp with relation thereto. It will be observed that when said bolt acts independently of the rotary plate, the abutments f^2 thereon merely swing away from those h^s h^s i' i' on said plate, the springs g' normally restoring the various parts to a position where said plate and its abutments will readily pick up and actuate said bolt through the abutments f^2 . The arrangement of said abutments also affords as great leverage as is possible in the area within the bolt chamber.

It will be further observed that by arranging the opening E' diagonally across the socket plate E , the points of contact of the oppositely disposed swinging or pivotal bolts will be substantially the same distance from the hasp pivot, thus insuring a substantially simultaneous engagement of both bolts, avoiding all binding of same upon their pivot, and distributing the wear.

It is apparent that the bolt casting need not necessarily be in a single piece as shown, as the opposite ends thereof are subjected to the action of separate springs and each head f is provided with an abutment f^2 acted on respectively by the rotary controlling plate.

In the interests of economy, however, I pre-

fer to make each said bolt head integrally with the other, and such a construction also minimizes the wear of parts. It is not my intention, however, to limit my invention to the precise details of construction herein shown and described, as it is apparent that such may be varied without departing from the spirit and scope of my invention.

Having thus described the invention, what I claim as new and desire to have protected by Letters Patent is:

1. In a lock, the combination of a lock cup comprising an upper or tumbler chamber, and a lower or bolt chamber of smaller dimensions than said tumbler chamber having an opening through the side thereof, a pivotal or swinging bolt mounted in said bolt chamber having its head normally projected through said opening, a spring acting on said bolt to normally project it from the bolt chamber, key controlled means whereby said bolt may be swung to withdraw said head within said bolt chamber and said bolt may rotate independently of said means, means supporting said cup, and a coöperating lock or socket plate having an opening adapted to receive the portion of said cup carrying said bolt, whereby said bolt may pass through said plate and engage the under side thereof.

2. In a lock, the combination of a lock cup comprising an upper or tumbler chamber, and a lower or bolt chamber of smaller dimensions than said tumbler chamber having an opening through the side thereof, a pivotal or swinging bolt comprising a central portion adapted to engage the wall of said bolt chamber and having a rounded corner to permit the rotation of said bolt, mounted in said bolt chamber, and a bolt head projected through said opening, a spring acting on said bolt to normally project it from the bolt chamber, key controlled means whereby said bolt may be swung to withdraw said head within said bolt chamber and said bolt may rotate independently of said means, means supporting said cup, and a coöperating lock or socket plate having an opening adapted to receive the portion of said cup carrying said bolt, whereby said bolt may pass through said plate and engage the under side thereof.

3. In a lock, the combination of a lock cup comprising an upper or tumbler chamber, and a lower or bolt chamber of smaller dimensions than said tumbler chamber having an opening through the side thereof, a pivotal or swinging bolt comprising a central portion adapted to engage the wall of said bolt chamber and having a rounded corner to permit the rotation of said bolt, mounted in said bolt chamber, and a bolt head projected through said opening, said bolt having a spring seat back of said head, a spring in said seat and acting against the wall of said bolt chamber, key controlled means whereby said

bolt may be swung to withdraw said head within said bolt chamber and said bolt may rotate independently of said means, means supporting said cup, and a coöperating lock 5 or socket plate having an opening adapted to receive the portion of said cup carrying said bolt, whereby said bolt may pass through said plate and engage the under side thereof.

4. In a lock, the combination of a lock cup 10 comprising an upper or tumbler chamber, and a lower or bolt chamber of smaller dimensions than said tumbler chamber having an opening through the side thereof, a pivotal or swinging bolt mounted in said bolt chamber 15 having its head normally projected through said opening, a spring acting on said bolt, an abutment on said bolt head within said chamber, a rotary plate having an abutment thereon opposed to said abutment on 20 said bolt head mounted within said tumbler chamber, key controlled means whereby said plate may be rotated to force said head within said bolt chamber and said bolt may rotate independently of said plate, means 25 supporting said cup, and a coöperating lock or socket plate having an opening adapted to receive the portion of said cup carrying said bolt, whereby said bolt may pass through said plate and engage the under side 30 thereof.

5. In a lock, the combination of a lock cup comprising an upper or tumbler chamber, and a lower or bolt chamber of smaller dimensions than said tumbler chamber having 35 an opening through the side thereof, a pivotal or swinging bolt mounted in said bolt chamber having its head normally projected through said opening, a spring acting on said bolt, an abutment on said bolt head within 40 said chamber, a rotary plate comprising an upper plate seated in said tumbler chamber and a lower plate projected into said bolt chamber into close juxtaposition to said bolt, said lower plate converging on the sides 45 from a substantially central point thereof, said plates having an abutment thereon opposed to said abutment on said bolt head, key controlled means whereby said plate may be rotated to force said head within said bolt 50 chamber, and said bolt may be rotated independently of said plate, means supporting said cup, and a coöperating lock or socket plate having an opening adapted to receive the portion of said cup carrying said bolt, 55 whereby said bolt may pass through said plate and engage the under side thereof.

6. In a lock, the combination of a lock cup comprising an upper or tumbler chamber, and a lower or bolt chamber of smaller dimensions than said tumbler chamber having 60 an opening through the side thereof, a pivotal or swinging bolt mounted in said bolt chamber having its head normally projected through said opening, a spring acting on said 65 bolt, an abutment on said bolt head within

said chamber, a rotary plate comprising an upper plate seated in said tumbler chamber and a lower plate projected into said bolt chamber into close juxtaposition to said bolt, said lower plate converging on the sides from 70 a substantially central point thereof, said plates being cut away to form a shoulder thereon opposed to said abutment on said bolt, and provide suitable ways for the key controlled mechanism, key controlled means 75 whereby said plate may be rotated to force said head within said bolt chamber, and said bolt may rotate independently of said plate, means supporting said cup, and a coöperating lock or socket plate having an opening 80 adapted to receive the portion of said cup carrying said bolt, whereby said bolt may pass through said plate and engage the under side thereof.

7. In a lock, the combination of a lock cup 85 comprising an upper or tumbler chamber, and a lower or bolt chamber of smaller dimensions than said tumbler chamber having an opening through the side thereof, a pivotal or swinging bolt mounted in said bolt 90 chamber having its head normally projected through said opening, a spring acting on said bolt, an abutment on said bolt head within said chamber, a rotary plate comprising an upper plate seated in said tumbler chamber, 95 and a lower plate projected into close juxtaposition to said bolt, said lower plate converging on the sides from a substantially central point thereof, said plates being cut away to form a shoulder thereon opposed to 100 said abutment on said bolt and provide suitable ways for the tumbler and tumbler spring studs, a tumbler and a tumbler spring stud carried by said cup within said tumbler chamber, a lock piece carried by said rotary 105 plate, a tumbler and tumbler spring mechanism mounted on said studs, and engaging said lock piece, a key barrel passing through said plate, said bolt and the means supporting said cup having shoulders thereon whereby it and said plate are held in place, means 110 supporting said cup and a coöperating lock or socket plate having an opening adapted to receive the portion of said cup carrying said bolt, whereby said bolt may pass through said plate and engage the under side 115 thereof.

8. In a lock, the combination of a lock cup comprising an upper or tumbler chamber and a substantially rectangular lower or bolt chamber extending diametrically across said tumbler chamber having diagonally opposite openings through the sides thereof, a pivotal or swinging bolt having oppositely disposed straight portions adapted to engage the walls 120 of said bolt chamber and having diametrically opposite rounded or beveled corners to permit the rotation of said bolt, bolt heads having rounded or beveled ends projected through said openings respectively, a plu- 125 130

rality of springs acting on said bolt on opposite sides of its pivot, key controlled means whereby said bolt may be swung to withdraw said heads within said bolt chamber 5 and said bolt may be rotated independently of said means, means supporting said cup, and a coöperating lock or socket plate having a substantially rectangular opening extending diagonally across said plate at an angle to 10 cause the bolts to engage the sides thereof on substantially the same geometrical straight

line parallel with the pivot of said cup support whereby said bolt may pass through said plate and engage the under side thereof.

In witness whereof, I have hereunto affixed 15 my signature this 15th day of November, 1905, in the presence of two witnesses.

FRANK S. ALIANO.
